UNITED STATES PATENT OFFICE

1,926,302

BARREL-HEAD FASTENER

George H. Osgood, Tacoma, Wash.

Application January 18, 1932. Serial No. 587,377

1 Claim. (Cl. 217—89)

This invention relates to means for fastening the head of a barrel in place thereon and has special reference to barrels and heads made of plywood.

5 The objects of my invention are to provide a fastening means which requires no nails and which, therefore, may be removed without damage either to the barrel, the head, or the fastening hoop, and which therefore permits the said parts 10 to be used as often as required; which is of great strength, which is cheap, and which is easy to apply or remove with simple tools.

I attain these and other objects by the devices and arrangements illustrated in the accompanying drawing, in which—

Fig. 1 is an elevation of the end of a barrel, showing the head fastened thereto; Fig. 2 is a plan view thereof, on a smaller scale; Fig. 3 is an enlarged section of the joint between the barrel and its head, taken on the line 3—3 in Fig. 2; Fig. 4 is a similar section taken on the line 4—4 in Fig. 2; Fig. 5 is an elevation of the two ends of the fastening hoop, disconnected; and Fig. 6 is a similar view of a variation thereof.

25 Similar numerals of reference refer to similar parts throughout the several views.

My invention applies primarily to plywood barrels but may be used with other types of construction. As shown in the drawing, the barrel 30 1 and the head 2 are of such plywood construction, the head 2 being usually of slightly thicker stock than the body of the barrel 1. The head 2 is of a diameter substantially equal to, but not greater than, the outside diameter of the 35 barrel 1 and is provided with a circumferential groove 3 extending entirely around its inner edge whereby it fits into the end of the barrel (Figs. 3 and 4) forming a lap-joint therewith.

The barrel 1 is provided with a circumferential 40 groove 4 in its outer surface, said groove 4 being parallel with the end of the barrel and being positioned about one inch therefrom. This groove 4 may, in practice be about one sixteenth 45 of an inch deep and wide.

The fastening means comprises an open hoop 50 formed of a cylindrical portion 5, having a small flange or gripping lug 6 turned inward therefrom along its entire lower edge and adapted to enter the groove 4 in the outer surface of the barrel 1 and to grip the upper edge thereof; and a holding flange 7 turned inward therefrom along its 55 entire upper edge and adapted to lie snugly on top of the outer edge surface of the head 2, to hold the head in place on the barrel, said flange 7

being about as wide as the thickness of the barrel stock.

The length of the cylindrical part 5 is slightly less than the circumference of the barrel 1 or head 2. Both ends of the cylindrical part 5 are 60 provided with tongues 8 adapted to overlap when the hoop is tightened around the barrel. These two overlapping tongues 8 may be clamped together by any of the accepted seals, 9 in common use at the present time. The tongues 8 are preferably of equal width and length (Fig. 5) but, if desired, one may be broader than the other and provided with a slot 10 through which the other tongue may be passed (Fig. 6), in which case the ends may be clamped or soldered together to fasten the hoop in place.

The barrel is headed by first placing the head 2 into and over the end of the barrel and then passing the hoop over the head and pressing it down until the flange 6 enters the groove 4 in 75 the barrel, at which time the flange 7 will be tight on top of the head 2. The clamp or seal 9 is then slipped over the lapped tongues 8 and the tongues are drawn tight enough to prevent the flange 6 from being removed from the groove 80 4, and the seal 9 is closed.

It is evident then that the head 2 is securely held on the end of the barrel. It cannot be pulled off therefrom by an axial pull, tests having shown that the barrel head will break before 85 the hoop will loosen from the barrel. It cannot be slid laterally both because of the groove 3 which forms a shoulder around the head and makes a lap-joint with the barrel, and because the hoop forms a stiff flange entirely surrounding 90 its edge. In practice, the strength of certain hoops has been found such that it takes a stress of 850 pounds per lineal inch to straighten out the flange 7 and 1290 pounds per lineal inch to 95 straighten out the flange.

It is to be understood that this hoop is not intended to act as the ordinary barrel hoop by reenforcing the barrel against bursting stress but is simply a means of holding the head 2 in place thereon. It is also to be understood that several changes may be made in the details of my invention, without departing from the essence thereof as outlined in the appended claim, such as:—the head 2 may lie altogether on top of the end of the barrel, or, in some cases, it may even lie within the end of the barrel and with its outer face flush with said end, in which case the flange 7 must be made wide enough to properly engage the outer surface of the head.

110

Having described my invention, what I claim, and desire to secure by Letters Patent, is:—

5 A barrel closure comprising a head closing the end of the barrel; an open hoop comprising a cylindrical portion encircling the end of the barrel, a lower inward-extending gripping flange and an upward inward-extending holding flange, said hoop being shorter than the circumference of the barrel; a pair of overlapping tongues ex-

tending from the ends of said hoop; a separate removable seal for securing said tongues together; a groove formed around the barrel adjacent to and parallel with its end and adapted to receive the lower gripping flange of said hoop, whereby said hoop is held from axial movement on the barrel.
